ELECTRON DISCHARGE TUBE

Gregorius Johan Lambert, Eindhoven, and
Johannes Willem Meyjes, Nymegen, Netherlands, assignors to Radio Corporation of America, a corporation of Delaware

Application July 29, 1932, Serial No. 625,846
In the Netherlands August 4, 1931

5 Claims. (CL 250—27.5)

This invention relates to electron discharge tubes, and more particularly to the manner of mounting the electrodes in such tubes.

It is one of the objects of the present invention to arrange the conductive parts within the tube in such a manner with respect to one another that perfect insulation between the said parts is obtained while at the same time resulting in a simple construction.

10 It is known that glass beads are generally used in electron discharge tubes in which the supporting and supply conductors of the different electrodes are frequently fixed together by means of such beads. Applicants have found however, that 15 the use thereof entails several drawbacks. For example, when these beads are used, the distances between the conductive parts fixed therein are often too small due to which short circuits may occur between said parts especially at high temperatures. 20 These short circuits may also result from conductive material depositing on the surface of the insulating body, which may bring about an electric connection between the parts fixed to the insulating body. Moreover, difficulties are sometimes encountered on account of 25 stress set up in such bodies by expansion of the parts secured thereto.

The present invention has for its purpose to avoid the drawbacks inherent in the use of such 30 insulating beads. In an electron discharge tube according to the invention two or more electrically conductive parts are connected together by means of a body consisting of insulating material which is mounted in the tube independently of 35 the wall thereof and provided with one or more recesses. In one or more of the recesses a conductive part may be fixed, whilst said recesses may also be provided between the conductive parts fixed in the body. It has been found that 40 a very suitable construction is obtained by constituting the body by two or more coaxial or substantially coaxial tubes, the conductive part being provided in the inner tube whereas another conductive part is fixed to the outer tube. Excellent 45 results may be obtained if the conductive part provided in the inner tube is movable in a longitudinal direction within this tube. Furthermore a suitable construction is obtained by securing to the outer tube one of the conductive parts in 50 form of or by means of a clasp surrounding this tube or by providing that the part attached to this outer tube is partly sunk therein.

By means of the constructions according to the invention the drawbacks referred to in the preamble may be avoided for the greater part since the so-called leakage path between the different conductive parts may be made much longer than that frequently obtained with the usual beads. Moreover, short circuits occurring between said 55 parts over the surface of the body due to deposits

of conductive material may be entirely avoided. Moreover the constructions referred to above permit the conductive parts to expand freely without stress being produced in the bodies consisting of insulating material.

Said bodies may also consist with advantage of 5 two or more coaxial insulating tubes which are connected together at one of the ends and closed at this end. However, they may also be constituted by two coaxial insulating tubes fixed together in the middle or about in the middle. Furthermore, there are several manners of securing the conductive parts in and to said bodies. One of said parts may be taken, for instance, through the inner tube, whereas another conductive part 10 is attached to the outer side of the outer tube. Moreover, it is also possible to secure on either side of an insulator formed in this way a conductive part in the inner tube and a third conductive part to the outer side of the outer tube. 15 In order to improve the insulation in the latter case the inner tube may be closed between both conductive parts, for instance, by heating and pinching it at this point.

Though in most cases said insulating bodies 20 may consist of glass it is also possible to use other insulating materials, for example, magnesium oxide.

The invention will be more clearly understood by reference to the accompanying drawing, representing, by way of example, some forms of construction thereof.

Fig. 1 shows the interior of a vacuum tube according to the invention.

Fig. 2 is a plan view of this tube,

Figs. 3, 4, 5 and 6 are detail views of forms of construction of the invention, and;

Fig. 7 is a plan view of Fig. 6.

In Figs. 1 and 2 the glass wall or envelope 1 of the electron discharge tube is provided with a 40 stem 2 and a pinch 3. Through the pinch are led the supply conductors 4 and 5 for the heater element, the cathode lead-in conductor 6, the lead-in conductor 7 to the control grid and that 8 of the screening grid. The anode lead 8a is led 45 in through the top of the envelope. Furthermore, the tube is furnished with an annular body 9 which by means of four supports 10 is fixed to the pinch. On this annular body is mounted the screening grid 10 (partly broken away for simplicity) and in addition the anode 20, whose supporting wires are connected to the said body by means of glass beads so as to be insulated therefrom. The anode which may be made of nickel is shown in Figs. 1 and 2 as two rectangular plates 50 20, although it may assume other suitable constructions, such as a flattened cylinder.

On the pinch 3 there are mounted two supporting rods 11 connected at the top by a cross bar 12 carrying a supporting member 13 to which is 55 60

fixed the cathode 14, shown in the drawing as an indirectly heated cathode. Said supporting member serves at the same time for the current supply to the cathode body. Attached to the end of 5 each supporting rod 11 and remote from the press is an insulating tubular member or bushing 15. Connected between these tubular members or bushings is the cross piece 16 which may be in the form of a metal strip and has the general contour shown in Fig. 2. The enlarged ends 10 of the member 16 substantially surround and are embedded within circumferential depressions provided on the outer surface of each tubular member 15, while the upper ends of the supporting rods 17 of the control grid 18 are clamped between opposite portions of the member 16 as indicated in Fig. 2.

By the use of said insulating bodies 15 which may consist, for instance, of glass and are connected together in the middle, the leakage path 20 between the supporting rods 11 and the conductive parts 16 is longer than that resulting from the use of glass beads of known construction. Moreover, in the present construction there is no risk of short circuits occurring over the 25 surface of said insulating bodies on account of deposits of material, and in addition the conductive parts to go with the electrodes may expand freely without the risk of a breakdown of the glass insulators.

In Fig. 3 there is shown another form of construction wherein the insulating body designated by 21 consists of a solid portion 22 and two recessed portions 23. Two conductors 23' are arranged within the recessed portions and are secured to the insulating body at 24. A third conductor 22' is sealed into the portion 22.

Fig. 4 shows another form of construction, in which the upper ends of the grid supporting rods 40 17 are slipped into two insulating bodies 26 which are closed at the top, a conductive part 27 being sunk into these bodies. By means of the fastening member 28 the part 27 has fixed to it the cathode 14, whereas the conductive parts 27 are used at the same time for the supply of current 45 to the cathode body.

In Fig. 5 the upper ends of the supporting rods 17 are positioned within two insulating bodies 31 which are closed at the top and around which is 50 provided a conductive part 32 in form of a clasp. To this part is secured a fastening member 33 which has attached to it the cathode 14 in the same manner as illustrated in Fig. 4.

Figs. 6 and 7 show a form of construction in 55 which three conductive parts are fixed to one insulating body. To this effect one of said tubular insulating bodies 15 is slipped over the end of each supporting rod 36 arising from the pinch of the discharge tube, the ends of said rods extending 60 within the insulators 15 but not penetrating to the middle thereof. To an intermediate part of each supporting rod 36 there is fixed a clasp or strap 37 which supports the fastening member 38 attached to the cathode 14. Into the other ends of the insulators 15 are inserted the conductive parts 49 to which are secured the two cross members 41 which in turn are fastened to the screening grid 42 through the rectangular end member 44. Finally fastening member 43 is attached 65 to the insulating bodies 15, as in Figs. 1 and 2, opposite portions of said member having fixed between them the supporting rods 17 of the control grid.

Though the drawing represents different forms

of construction it will be understood that a great many modifications are possible without departing from the scope of the invention and by means of which it is also possible to yield the advantages resulting from the invention. It is possible, for instance, to secure a plurality of conductive parts to the outer side of the bodies referred to above, whereas said bodies may be given various shapes.

What is claimed is:

1. In an electron discharge tube, an evacuated envelope having a reentrant stem, anode, cathode and grid electrodes within the envelope, a pair of vertical support rods carried by the stem, a tubular insulating member mounted adjacent the 15 end of each support rod remote from the stem, said support rods extending beyond the tubular members, a cross member joining the said extended ends of the support rods, a conductor connected between said cross member and the cathode, 20 a pair of support rods for the grid electrode arranged close to the first mentioned support rods and also carried by the stem, and means carried by the tubular insulating members engaging the grid electrode supports. 25

2. In an electron discharge tube, an evacuated envelope having a reentrant stem, an electrode support rod extending above the stem and having one of its ends sealed therein, a laterally extending member rigidly secured to the opposite end 30 of said support rod, a second support rod substantially coextensive with said electrode support rod and also having one of its ends sealed in said stem, and an insulating bushing slidably mounted on the opposite end of said second support rod 35 and having a connection with said laterally extending member.

3. In an electron discharge tube, a press, a pair of spaced vertical support rods carried by the press with one of their ends sealed therein, 40 means for insulatingly connecting together the other ends of said support rods which are remote from the press, comprising a tubular insulating member rigidly fixed to and carried by one of said support rods at that end remote from the 45 press, the adjacent end of the other support rod arranged to slidably engage within the tubular insulating member.

4. In an electron discharge tube, a press, a plurality of spaced parallel support rods having 50 one of their ends mounted in said press, means for insulatingly connecting together the other ends of said support rods, comprising a tubular insulating bushing loosely fitted over the last mentioned end of one of the support rods, and a 55 connection between the adjacent end of the other support rod and the outer surface of the insulating member.

5. In an electron discharge tube, an evacuated envelope having a reentrant stem, anode, cathode 60 and grid electrodes within the envelope, a pair of vertical support rods carried by the stem, a cross-member joined to the ends of the support rods remote from the stem, a conductor connected between said cross-member and the cathode, an 65 insulating sleeve member slidably mounted upon each of the vertical support rods at that end adjacent to the cross-member, and a pair of grid electrode supports, each having one end fixed to the stem and the other end rigidly connected to 70 one of the insulating sleeve members.
